UNITED STATES PATENT OFFICE

MARGARET GARRETT, OF DETROIT, MICHIGAN

DESIGN FOR A KNIFE

Application filed October 31, 1932. Serial No. 45,662. Term of patent 14 years.

To all whom it may concern:

Be it known that I, MARGARET GARRETT, a citizen of the United States of America, residing at Detroit, in the county of Wayne and State of Michigan, have invented a certain new, original, and ornamental Design for a Knife, of which the following is a specification, reference being had therein to the accompanying drawing, forming part thereof, in which Fig. 1 is a perspective view of the knife; Fig. 2 is a side elevation of the knife; and Fig. 3 is a top plan view of the knife.

I claim:

The ornamental design for a knife, substantially as shown.

In testimony whereof I affix my signature.

MARGARET GARRETT.
